UNITED STATES PATENT OFFICE.

LINNAEUS E. BAKER, OF FORT WAYNE, INDIANA, ASSIGNOR TO WAYNE TANK & PUMP COMPANY, OF FORT WAYNE, INDIANA, A CORPORATION OF INDIANA.

STOP MECHANISM.

Application filed October 10, 1922. Serial No. 593,570.

To all whom it may concern:

Be it known that I, LINNAEUS E. BAKER, a citizen of the United States, residing at Fort Wayne, in the county of Allen and 5 State of Indiana, have invented new and useful Improvements in Stop Mechanisms, of which the following is a specification.

My invention relates to combinations of machine elements constituting stop mechanisms, such as dispensing apparatus used 10 for gasoline or oil and particularly to means for limiting the movement of the pump piston or other suitable moving part to insure discharge of the quantity of liquid 15 desired to be dispensed at that pumping.

The invention consists of a new combination of stop rod and stops thereon and is characterized by few and simple parts and ease of manipulation.

20 The object of the invention is to throw into acting position any of the stops desired, by simply giving that stop a partial rotation instead of first rotating another stop or other stops out of position and then rotate the desired stop into position.

Another object of the invention is to conserve space by using only a limited segmental space, instead of circling entirely around the stop rod.

30 The particular embodiment of my invention selected for illustration is a measuring pump of the rack and pinion type, adapted to dispense liquid on the up stroke of the piston.

35 Figure 1. is such a measuring pump shown in side elevation, a part of the gear casing being in section, with my improved stop rod and stops in position, set to pump two units of measure, the mechanism being broken away just below the top cylinder head.

Fig. 2, a detail, is a vertical section on the line 2-2 of Fig. 1.

Fig. 3, a detail, is a perspective of the 45 upper part of the stop mechanism.

Fig. 4, is a cross section on the line 4-4 of Fig. 2.

Fig. 5, is a cross section on the line 5-5 of Fig. 2.

50 Referring now to the drawings, G, is the gear rack fixed to the piston rod, P, for reciprocating the pump piston. A projecting lug, g, on the rack G, extends toward the stop rod, R, far enough to be in contact 55 with one of the stops, S, and arrest the

motion of the rack, when said stop is set in using position like the three upper ones in Fig. 1, and the rack is then raised by operating the pump. Obviously only the lowermost of the stops in using position will 60 be engaged by the lug, g; but it is a peculiarity of the mechanism of this invention that whichever of the stops is set in using position, all the stops about it are simultaneously and by the one motion of setting, 65 thrown into like position. Likewise whenever any stop is swung out of using position, all the stops below it are simultaneously and by the one motion thrown out of using 70 position.

The rod, R, is fixed in substantially vertical position and the stops, S, are rotatively seated thereon one above another, either abutting as shown in the drawings or with spacing washers between.

Under each stop, S, are two recesses, r, usually formed by "spotting" with a drill, or of course the rod could have two longitudinal slots. In either of these recesses, r, a steel ball, s, seats under pressure of the 80 spring, s². One recess is so placed as to keep the stop in position when aligned for contact with the stop lug, g, and the other to keep the stop out of contacting position with the lug, g, when not set for use.

85 Each stop has a handle, s³, for convenience in rotating it into and out of using position.

Each stop is drilled on the front or projecting end, s¹, parallel with the rod R, and threaded to receive a set screw, s⁴, and the head of this set screw is drilled, at s⁵, to receive a sealing wire, s⁶. Above the projecting end, s¹, is a fin, s⁹, pierced by a hole, s⁷, to receive the sealing wire, s⁶, and on its 95 under side is a downwardly projecting lug, s¹⁰, adapted to contact with the fin, s⁹, of the next lower stop, S, when their projections, s¹, are in alignment. A similar lug, h, is also provided on the housing H, for the 100 topmost stop and another, h², for the bottom. A seal, s⁸, is used in the ordinary manner after the set screw, s⁴, has been adjusted to proper measuring position.

An adjustable set screw, h¹, with seal 105 guard, h², is adapted to determine the maximum pumping stroke of the piston, by contact of the lug, g, therewith when all the swinging stops are rotated out of using position.

Numbers may be provided on the stops or on an adjacent part of the housing opposite each stop, to indicate the gallons or other units of measure the pump is set to dispense, when said stop is brought into engaging position with the lug on the rack.

Obviously many changes may be made in the device herein shown, to suit the various types of dispensing mechanism, without departing from the spirit of my invention.

I claim as my invention and desire to secure by Letters Patent of the United States:

- 15 1. A shaft with a plurality of machine elements longitudinally mounted thereon and adapted to be rotated a part rotation and means on said elements adapted by the forward rotation of any of said elements to insure the forward rotation of all elements on one side of the positively rotated element not already in the forward position, and means on said elements adapted by the backward rotation of any of said elements to insure the backward rotation of all elements on the other side of the positively rotated element not already in the said backward position.
- 20 2. In combination with a moving part of a dispensing apparatus; a quantity stop rod substantially parallel with said moving

part; a plurality of stops on said rod, and means on said stops for producing the simultaneous rotation into using alignment of all stops out of using alignment on one end of the one so rotated, by such rotation of the one for use; and means for producing the simultaneous rotation out of using alignment of all stops not already out of using alignment on the other end of any one so rotated by such rotation.

3. In combination with a projection on the reciprocable operating means of a measuring pump; a quantity stop rod substantially parallel with said operating means; a plurality of stops on said rod, and means on said stops for producing the simultaneous rotation into using alignment of all stops out of using alignment above the one so rotated, by such rotation of the one for use; and means for producing the simultaneous rotation out of using alignment of all stops not already out of using alignment below any one so rotated by such rotation.

In testimony whereof I have hereunto set my hand in presence of two subscribing witnesses.

LINNAEUS E. BAKER.
